DESIGN FOR A NET FABRIC OR SIMILAR ARTICLE

Daniel Gross, Yonkers, N. Y.

Application April 20, 1937, Serial No. 68,888

Term of patent 3½ years

To all whom it may concern:

Be it known that I, Daniel Gross, a citizen of the United States of America, residing in Yonkers, New York, county of Westchester, and State of New York, have invented a new, original, and ornamental Design for a Net Fabric or Similar Article, of which the following is a specification, reference being had to the accompanying drawing, forming part thereof.

The figure is a plan view of a net fabric or similar article showing my new design, the repeat unit is contained between the two horizontal dot and dash lines and the two vertical dot and dash lines.

I claim:

The ornamental design for a net fabric or similar article as shown and described.

DANIEL GROSS.
